DESIGN FOR A STATION WAGON TYPE AUTOMOBILE

Clifford Brooks Stevens, Milwaukee, Wis., assignor to Monart Motors Inc., Milwaukee, Wis., a corporation of Wisconsin

Application June 21, 1943, Serial No. 110,496

Term of patent 3½ years

To all whom it may concern:

Be it known that I, Clifford Brooks Stevens, a citizen of the United States, residing at Milwaukee, in the county of Milwaukee and State of Wisconsin, have invented a new, original, and ornamental Design for a Station Wagon Type Automobile, of which the following is a specification, reference being had to the accompanying drawing, forming part thereof.

of a station wagon type automobile showing my new design.

The opposite side, not illustrated, is identical in appearance with the side shown.

The dominant features of my design are shown in full lines in the drawing.

I claim:

The ornamental design for a station wagon type automobile, substantially as shown and described.

CLIFFORD BROOKS STEVENS.
